United States Patent Office.

WILLIAM HENRY GROVE, OF PHILADELPHIA, PENNSYLVANIA.

Design No. 4,477, dated November 15, 1870.

DESIGN FOR A SHOW-CASE.

The Schedule referred to in these Letters Patent and making part of the same.

I, WILLIAM HENRY GROVE, of Philadelphia, county of Philadelphia, State of Pennsylvania, have invented or produced a Design for Show-Case, of which the following is a specification.

On reference to the accompanying drawing—

Figure 1 is a side view of a show-case made in accordance with my design;

Figure 2, a perspective view of the same; and

Figure 3, a perspective view of a modification.

The case represented in figs. 1 and 2 has a rectangular base, *a*, and top, *b*, and all four of the sides *c* of the lower portion of the case are inclined outward and upward from the base to the point *x*, where they meet the sides *d* of the upper portion of the case, which incline inward toward the top plate *b*.

The base *a* may be ornamented in any appropriate manner, and should project outward slightly from the

body of the case, so as to give the latter the appearance of a well-proportioned casket.

The sides may be connected together, and to the top, by any suitable molding, and they may be of any desired number, and at any degree of inclination.

Claim.

A show-case, having double-inclined slides, substantially as described, and as represented in and by the accompanying drawing.

In testimony whereof, I have signed my name to this specification in the presence of two subscribing witnesses.

W. H. GROVE.

Witnesses:

WM. A. STEEL,
HARRY SMITH.
